UNITED STATES PATENT OFFICE.

TRUMAN B. FUNK, OF MOLINE, ILLINOIS, AND CLARENCE M. EASON, OF HARRISON, NEW JERSEY; SAID EASON ASSIGNEE TO SAID FUNK.

ENGINE GOVERNOR.

1,410,462.

Specification of Letters Patent. Patented Mar. 21, 1922.

Application filed July 31, 1920. Serial No. 400,329.

To all whom it may concern:

Be it known that we, TRUMAN B. FUNK and CLARENCE M. EASON, both citizens of the United States, residing at Moline, Rock Island County, Illinois, and at Harrison, Hudson County, New Jersey, respectively, have invented certain new and useful Improvements in Engine Governors, of which the following is a specification.

10 This governor is intended primarily for use as a gas engine governor on tractors and is peculiarly fitted to conform to the requirements of that use, although it is not the intention that the invention be limited 15 to the use stated.

The object and purpose of this invention is to construct a governor which will automatically regulate the speed of an engine regardless of the change in load. The present governor is so designed that it may be adjusted by the operator from his seat to govern the engine over a wide range of low speeds, so that flexibility of control is afforded and substantially constant speed 25 ratios maintained within the selected range.

Further objects and uses of the invention will appear from a detailed description of the same which consists in the features of construction and combinations of parts hereinafter described and claimed.

In the drawings:

Figure 1 is a sectional elevation of the governor with the casing cut away;

Fig. 2 is a side elevation of the exterior of 35 the casing;

Fig. 3 is a top or plan view with the cap removed; and

Fig. 4 is an exterior elevation at right angles to that of Fig. 2.

40 The governor is housed within a cup-shaped casing 5 closed by a cap 6 and provided with a base 7 from which depends a tubular sleeve 8. The housing is mounted on some convenient portion of the engine 45 casing and serves as an enclosure within which the working portions of the governor are housed.

50 Journaled within the sleeve 8 is a vertically disposed rotating tubular shaft 9 provided at its upper end with a flanged head 10 which affords a base or support for a pair of standards 11 which rotate with the shaft and between which two weights 12 are mounted upon pivot pins 13. Each of 55 the governor weights is provided at its upper

end with an inwardly extending finger 14 which projects into a slot 15 in the bifurcated head 16 of a post 17 which is slidably mounted within the bore in the center of the tubular shaft 9 and rests upon the coiled 60 spring 18, the arrangement being such that, as the weights fly out through the effect of centrifugal action, the inwardly projecting fingers 14 bearing upon the post 17 will cause the latter to be depressed against the 65 tension of the spring.

The upper end of the slotted head 16 has fixedly mounted thereon a collar 16^a within which the head rotates, which collar is provided on each side with a trunnion 19, 70 the two trunnions furnishing pivotal bearings for a pivot yoke 20 preferably formed of two sections of metal plate bowed to embrace the trunnion head, the sections having their ends united to provide ears 21 and 22 one of which receives the outer end of a bent arm 23, and the other the end of a similar arm 24, the two arms being pivotally mounted through bosses 25 and 26 on diametrically opposite sides of the housing so 75 that the two bent arms will turn in the same axial line.

The bent arm 23 has clamped thereon a lever arm 27 provided at its upper end with a plurality of holes 28 for permitting variable adjustments. The protruding end of the bent arm 24 has clamped thereto a control lever 29 whose range of movement can be regulated by means of a pair of adjusting screws 30 entered through lugs 31 on the 80 exterior of the housing and adapted to be held in adjusted position by lock nuts 32.

Rotary motion is imparted to the shaft 9 and governor carried thereby by means of a pinion 33 or the like keyed or otherwise secured upon the lower end of the bore shaft 9. This pinion may be put in train with any appropriate rotating portion of the engine.

In use the employment of the two levers 27 and 29 will ensure a range of adjustments 100 and a flexibility of control such that the governor will operate within varying speed limits in a manner now to be described. By moving the lever 27 to the right in Fig. 3, the bent arm 23 will be rocked downwardly. 105 This movement will depress the corresponding end of the yoke 20, thereby swinging the yoke upon the arm 24 as a fixed pivot, and serving to depress the spring supported post 16 by an amount equal to one-half the move- 110

ment of the depressed end of the yoke. This depression of the post lowers the same away from contact with the inturned fingers 14 of the governor weights, so that with the adjustment indicated, the speed of the engine must be increased to a predetermined degree before the governor weights will rise to such position as to again bring the fingers 14 in contact with the post. This adjustment permits the engine to acquire a predetermined speed before the governing action of the weights begins to operate. Thereafter an increase of speed will have the effect of causing a further depression of the spring operated post; and with the arm 27 in locked relation and the control arm 29 free to move, the action of the weights will, of necessity, be centered upon the movable control arm, so that a continued drawing down of the yoke will cause a greater or less degree of movement to be imparted to the control arm, thereby operating the throttle to cut down the gas supply to a degree commensurate with the governing movement, with the result that the throttle action will be maintained in a state of equilibrium depending upon the action of the governor weights.

The co-action between the adjusting lever 27 and the control lever 29 is such that the adjusting lever can be moved to any desired position, or can be permitted to remain in normal position, as shown in the drawings, and this movement of the adjusting lever serves to determine the range within which the governor action will be limited. Thus when a slow speed of adjustment is desired, the spring post can be maintained in its uppermost position and in contact with the governor fingers while the engine is at rest. Thereafter, the initiatory movements of the governor weights will cause a depression of the spring post and a consequent throttling effect within a low speed range. Similarly by moving the adjusting lever to varying positions, the range of governing action can be adjusted for higher speeds, so that the present device enables the operator to select the desired speed and adjust the governor to maintain such speed under varying loads due to ground inequalities or other causes.

With the governor in its low speed adjustment, the range of action of the governor weights will be limited to an arc within which the weights will depart but a small degree from their normal vertical position, and the lever arm effective for counteracting the tension of the spring 18 will be relatively long. Thus a relatively slow engine speed will be effective to impart to the governor weights a sufficient divergence from vertical position to depress the spring and effect closing of the throttle.

When the post is depressed to set the governor for operation in a higher speed range, this adjusting movement will effect an ini-

tial compression of the spring, and will also retract the point of contact for the weights, so that thereafter an initiatory movement of the weights will be necessary to effect operative contact of the weights and the post. Thereafter the effective action of the weights at a higher rotary speed will begin, and the weights, operating within a range of movement more nearly approaching the horizontal, will operate on a shortened lever arm as against increased spring pressure so that a higher speed range will be required to effect a further compression of the spring and a resultant movement of the post such as to effect the closing of the throttle. Similarly for higher speed ranges the spring pressure will be further increased and the lever length further diminished to zero as the weights approach the horizontal position.

We claim:

1. In a governor, the combination of a slidably mounted stem, a rotatable standard arranged laterally of the stem, a weight pivoted to the standard and having a projecting member adapted to engage the stem when the weight is subjected to the action of centrifugal force, a spring bearing against the stem for resisting the action of centrifugal force, single adjusting means for regulating the position of the stem with respect to the contacting member on the weight and concurrently regulating the spring tension, and throttle controlling means adapted to be actuated by the action of the governor weight, substantially as described.

2. In a governor, the combination of a rotating governor weight, a spring supported stem adapted to be contacted and moved by the governor weight when rotated, a yoke pivotally connected to the stem, an adjusting device connected to one end of the yoke for regulating the position of the stem with respect to the governor, and a throttle controlling device connected to the other end of the pivoted yoke, substantially as described.

3. In a governor, the combination of a rotating governor weight, a stem adapted to be contacted and moved by the governor weight when rotated, a yoke pivotally connected to the stem, an adjusting device connected to one end of the yoke for regulating the position of the stem with respect to the governor, and a throttle controlling device connected to the other end of the pivoted yoke, substantially as described.

4. In a governor, the combination of a rotatable governor weight, a spring supported stem adapted to be contacted and moved by the weight when rotated, a pivotal member carried by the stem, two bent arms one pivoted to each end of the pivotal member and journaled in opposite relation to one another, an adjusting member connected to one of the bent arms for adjusting

the position of the stem with relation to the governor weight, and a throttle controlling member connected to the other bent arm for regulating the throttle within the range 5 of governing movements established by the adjusting member, substantially as described.

5. In a governor, the combination of a housing, a shaft rotatably mounted within 10 the housing, a spring pressed stem slidably mounted through the axis of the shaft, a pair of governor weights pivotally carried by the shaft and having their acting ends in co-acting relation with the stem, a member 15 pivotally mounted on the stem, bent arms, one connecting end each of the pivotal member, the bent arm being respectively journaled through the housing on diametrically opposite sides, an adjusting lever connected 20 to the protruding end of one of the bent arms, and a throttle controlling lever connected to the protruding end of the other

bent arm, the adjusting lever serving to vary the relation between the stem and the governor weights to establish speed limits with 25 in which the governor is effective to control the throttle, substantially as described.

6. In a governor, the combination of a governor weight rotatably mounted and pivoted to permit of a swinging movement 30 under the action of centrifugal force, means under the control of the governor weight for operating the throttle, means for exerting a pressure on said throttle operating means counter to the pressure exerted by the weight 35 when rotated, and a single means for jointly regulating the application of said counter pressure and for allowing the weight to initially move through a zone of regulated extent before it assumes a position in which to 40 operate the throttle controlling means, substantially as described.
